CAPSTAN OR LIKE HAULING MEANS

Rupert Francis Head, Burraneer Bay, near Sydney, New South Wales, Australia, assignor of one-half to Hoskins Estate Company Pty. Limited, Sydney, New South Wales, Australia, a company of New South Wales

Application September 4, 1941, Serial No. 409,455
In Australia November 5, 1940

3 Claims. (Cl. 254—150)

This invention has relevance to improved capstan or like hauling means for raising or lowering anchors, nets, or other articles or constructions.

Said improved capstan or like hauling means comprise a suitably journalled spindle. Upon the latter is loosely mounted a rotatable rope carrying barrel; in the circumferential wall of the barrel are two or more spaced recesses to receive a tommy bar, and also on the bottom face of the barrel are two or more spaced dowels adapted to cooperatively engage recesses in the upper face of a gipsy wheel which also is loosely mounted on said spindle below said barrel. A fixed collar is associated with the spindle below said wheel. A ratchet wheel can be mounted on the upper portion of said spindle, and a spring controlled pawl is associated with the said barrel and is adjustable for relative cooperative action with said ratchet wheel. A tapped cap with flat bottom face is adapted to cooperate with a flat upper face on said barrel, the said cap having two or more recesses in its circumferential wall adapted to receive a tommy bar. Said cap is also adapted to fit the externally screw-threaded upper end of said spindle. All of the said elements are arranged for operation with or without power drive means for the purposes and in the manner hereinafter referred to.

The said spindle may be adjustably couplable to another spindle, the latter spindle having associated therewith gear drive means couplably associated with power drive means.

Further, the pawl and its control spring can be carried in a recess in the circumferential wall of the barrel, the pawl being carried on one end of a spindle whose other end carries a finger knob externally of said wall. The barrel also has in its said wall two spaced openings adapted to be engaged by a pin projecting from said knob, so that the rotational direction of the ratchet wheel can be altered, or whereby when said pin is made to engage the exterior of said circumferential wall the said pawl will be kept out of engagement with said ratchet wheel.

Other features of the invention are herein-after referred to in the fuller description of the invention made with reference to the accompanying drawing, in which: Fig. 1 is a perspective view of capstan means according to the invention and adapted to be driven either manually or by power; Fig. 2 is a central sectional elevation thereof; Fig. 3 is a sectional plan on line 3—3 of Fig. 2; Fig. 4 is a detail sectional view; Fig. 5 is a sectional plan on line 5—5 of

Fig. 2; and Fig. 6 is an elevation of capstan means constructed for manual operation.

The spindle 1 of the capstan is vertically disposed and has a fixed collar 2 upon which is adapted to rest a gipsy wheel 3 which is loosely mounted on the spindle 1. The winding barrel 4 is adapted to cooperate with the gipsy wheel 3, the barrel 4 being also loosely mounted on the spindle 1; in the bottom face of the barrel 4 are two or more spaced vertically disposed dowel pins 5. Dowel pins 5 can enter recesses 6 in the upper face of the gipsy wheel 3 whereby the latter and the winding barrel 4 are cooperatively connected to be rotated simultaneously. In the head of the barrel 4 is a recess 7 in which can be accommodated a ratchet wheel 8 of suitable design. Wheel 8 can be loosely mounted on a rectangular boss 9 near the upper end of the spindle 1.

A spring loaded pawl 10 can be made to engage with the ratchet wheel 8, or pawl 10 can be held out of engagement with the wheel 8; the pawl 10 is slidable horizontally within a recess 11 in the circumferential wall of the head of the winding barrel 4. The pawl 10 is secured on the inner end of a spindle 12; the latter is slidable in a bearing 14 therefor in the barrel 4; its outer end is fitted with a manually operable knob 15 which projects beyond the said wall of the head of the barrel 4. Knob 15 can carry a projecting pin 17 which can be made to engage a pair of diametrically disposed recesses 18 in the circumferential wall of the head of the barrel 4. Through operation of the pawl 10 for engagement with the respective recesses 18, the said pawl can be altered in relation to the direction in which the ratchet wheel 8 is to be rotated. The pawl 10 can also be placed in neutral position by turning the knob 15 whereby the pin 17 will be made to engage the said circumferential wall of the head of the winding barrel 4, and thus pawl 10 will be kept out of engagement with the ratchet wheel 8 (Fig. 4). In the barrel 4 near its upper end are a plurality of spaced openings 19 any one of which may receive one end of a tommy bar 20. The upper end of the spindle 1 can be externally screw-threaded as at 21 to receive a tapped cap 23; the latter also has a plurality of spaced openings 24 in its circumferential wall to receive one end of the tommy bar 20 when it is not in use for the openings in the barrel 4. The under face of the cap 23 is flat and can be made to engage with the upper face of the barrel 4 which is also flat.

Below the collar 2 on the spindle 1 the latter can be journalled in a bearing bracket 26, which may be secured to a decking or other support by screw bolts or other suitable means. The extended end of the spindle 1 below the bracket 26 can be slidably secured in a coupling 27 by a set screw 28. Another spindle 30 also can be slidably secured by a set screw 29 in the coupling 27, the spindle 30 at its lower end being journalled in a bearing 31 and also a footstep bearing 32; both bearings 31 and 32 are within a gear casing 33. Keyed or otherwise suitably secured to the spindle 30 is a gear wheel 34 which can be made to mesh with a worm wheel 35 on a drive shaft 36 having bearing in the gear casing 33, the shaft 36 being connectible for rotation to any suitable power drive means.

In operation, when the capstan means are to be used for hauling-in purposes with associated power means, the pawl 10 is set so as to drive the barrel 4 with the spindles 30 and 1 and also to prevent the barrel 4 with its gipsy wheel 3 running backwards; simultaneously the barrel 4 and gipsy wheel 3 will be operatively connected together and to the spindle 1 and the whole of the said three components—barrel 4, gipsy wheel 3 and spindle 1—can be rotated by the power drive means 34 and 36 associated with the spindle 30 and the coupling means 27, 28 and 29. The barrel 4 can have wound thereon a suitable hauling rope. The gipsy wheel 3 can be used with any suitable hauling chain.

If the capstan means are to be operated manually the power is disconnected from the said power drive means so that the spindles 30 and 1 and the wheel 8 will be held stationary. The barrel 4 with the gipsy wheel 3 can then be rotated on the fixed spindle 1 by arcuately manipulating the tommy bar 20 in association with any of the holes 19 of the barrel 4. In such operation the pawl 10 will permit clockwise rotation (as seen in Fig. 4) of the barrel 4 relative to the stationary wheel 8; but, as long as the pawl 10 engages the recesses in the wheel 8, it will prevent backward running of the barrel 4 and gipsy wheel 3.

For running-out purposes of the hauling rope or chain, the power means before mentioned remain stationary; the pawl 10 is also placed in neutral position (Fig. 4) thereby operatively disconnecting the barrel 4 and gipsy wheel 3 from the spindle 1, the latter remaining stationary. To enable manual control of the speed of the barrel 4 and gipsy wheel 3 during running-out operations, the tommy bar 20 can be inserted in one of the openings 24 in the cap 23 and the latter can thus be readily screwed down by arcuate manipulation of the bar 20 upon the upper surface of the barrel 4, the contact of the bottom surface of the cap 23 with the upper surface of the barrel 4 serving as clutch and brake means for the barrel 4 and gipsy wheel 3.

When it is desired to use the capstan means without power means associated therewith (Fig. 6), the spindle 1 at its lower end can be screw-threaded to receive a cooperative nut 39 whereby the spindle can be rigidly secured in a bracket

33. There is also an opening 37 in the collar 2 which is adapted to receive a dowel pin 40 which is rigidly affixed to the upper portion of the bracket 38. The barrel 4 with its gipsy wheel 3 is rotatable on the fixed spindle 1 by inserting the tommy bar 20 into any one of the openings 19 in the winding barrel 4 and arcuately operating same. In such operation the pawl 10 is out of engagement with the wheel 8 but to prevent backward running of the barrel 4 and gipsy wheel 3 the pawl 10 is placed in engagement with the wheel 8. Clutching and braking of the barrel 4 and gipsy wheel 3 can be effected as before-mentioned by operating the cap 23 in relation to the barrel 4 by using the tommy bar 20.

The bracket 38 can be secured to a decking or any other suitable support by screw bolts or other suitable means.

When the barrel 4 is removed from the spindle 1 the gipsy wheel 3 can be placed on the spindle 1. Any gipsy wheel 3 of required chain pitch can be fitted to the spindle 1 by sliding any particular gipsy wheel 3 onto the spindle 1 and then replacing on the spindle 1 the barrel 4. Both the cap 23 and barrel 4 may be constructed of different metals.

What I claim as my invention and desire to secure by Letters Patent is:

1. Capstan or like hauling means comprising a suitably journalled spindle upon which is loosely mounted a rotatable rope carrying barrel, said barrel having in its circumferential wall two or more spaced recesses to receive a tommy bar and also on its bottom face two or more spaced dowels, a gipsy wheel loosely mounted on said spindle below said barrel and having recesses in its upper face to cooperatively engage said dowels, a fixed collar associated with said spindle below said wheel, a ratchet wheel mounted on the upper portion of said spindle, a spring controlled pawl associated with said barrel and adjustable for cooperative action with said ratchet wheel, a tapped cap with flat bottom face adapted to operate with a flat upper face on said barrel and having two or more spaced recesses in its circumferential wall adapted to receive a tommy bar, the said cap also fitting the externally screw-threaded upper end of said spindle.

2. Capstan or like hauling means according to claim 1, in which the spindle is adjustably couplable to another spindle, the latter spindle having associated therewith gear drive means couplably associative with power drive means.

3. Capstan or like hauling means according to claim 1, in which the pawl and its control spring are carried in a recess in the circumferential wall of the barrel, the pawl being carried on one end of a spindle whose other end carries a finger knob externally of said wall, and the barrel also has in its said wall two spaced openings adapted to be engaged by a pin projecting from said knob so that the rotational direction of the said ratchet wheel can be altered, or whereby when said pin is made to engage the exterior of said circumferential wall the said pawl will be kept out of engagement with said ratchet wheel.

RUPERT FRANCIS HEAD.
